SLIDE VIEWER

Michael S. Wolk, Miller, Ind.

Application February 29, 1956, Serial No. 40,404

Term of patent 14 years

(Cl. D61—1)

I claim:

The ornamental design for a slide viewer, substantially as shown.
